UNITED STATES PATENT OFFICE.

HALL H. HOLDAWAY, OF LOS ANGELES, AND THOMAS D. CAMPBELL, OF PASADENA, CALIFORNIA.

SLUSH PUMP.

Application filed November 6, 1924. Serial No. 748,089.

This invention relates to the type of pumps that are used in the construction of oil wells for pumping flushing fluid down into the wells, such flushing fluid generally consisting of a more or less thickened mixture of mud and water.

The slush pump in the present use requires a great deal of repair work and has a relatively short life for the reason that the mud pump operates to cut out very rapidly the packing of the pump piston. The general construction of the slush pump in common use embodies a pumping chamber within which is positioned a piston, the chamber being closed at both ends so that the piston may ordinarily force the fluid out from the opposite sides of the piston. When it is necessary to repair the piston or packing, it is necessary to take off the head at one end of the piston to reach the packing and frequently necessary to remove the liner of the pump chamber. This involves a considerable loss of time and expense.

An object of the present invention is to provide a pump for this class of work which will be less affected by the mud being pumped and the parts of which may be more readily repaired as the same wear. In carrying out our invention, in place of employing a piston within the pump chamber, we employ a long plunger which extends out from the chamber and in place of providing any packing between the chamber and piston, the plunger is packed exteriorly of the chamber where such packing is readily accessible for repair. Moreover, the plunger is made of substantially less diameter than the diameter of the chamber so that wear of mud upon the chamber walls is substantially reduced. With such a pump is incorporated means adjacent the packing to guide the mud in the pump and permit the same to settle so that the mud does not tend to force its way between the packing and the plunger, thereby preventing such mud from tearing out the packing of the plunger. In addition, in carrying out this invention, we provide a means by which such settled mud may be withdrawn as desired from the pump chamber.

Another object of the present invention is to provide a means in such a pump for preventing mud settling and packing in the chamber below the pump.

Another object of the present invention

is to provide a pump of this type with a removable shell for the plunger, whereby upon such wear of the plunger as takes place a new shell may be provided without requiring the replacement of an entire new plunger.

Various other objects and advantages of the invention will appear from a description of a preferred embodiment of our invention, for which purpose reference is made to the accompanying drawings.

In the accompanying drawings:

Figure 1 is an elevation of a pump embodying the invention, part of the figure being in section.

Fig. 2 is an enlarged sectional view of the packing and mud removing means.

Fig. 3 is a section on the line 3-3 of Fig. 1.

Fig. 4 is a detail partially in section of the plunger and cross bar connections therefor.

Fig. 5 is a detail of certain modifications in the mud settling means of the pump which may be incorporated in such pump as is shown in Figs. 1 to 4, inclusive.

Referring to the drawings, 1 indicates a pump casing providing two aligned pump chambers 2 and 3, said chambers being separated by a transverse wall 4. 5 and 6, respectively, indicate plungers mounted to reciprocate within the chambers 2 and 3, respectively, each of the plungers being of a length sufficient to extend exteriorly of the pump chamber and to permit such plungers to be there packed. As shown in Fig. 3, the ends of the pump chambers 2 and 3 are provided with annular flanges 7 through which bolts 8 extend, said bolts maintaining a packing box 9 to the casing 1 of the pump, the packing boxes 9 being provided with an annular recess 11 around the plungers, which recess 11 is disposed at the end of the packing box adjacent the pump chambers and is deepened at its lower end as indicated at 12 to provide a mud settling chamber 13. To the bottom of the mud settling chamber is connected a pet cock 14, which may be opened and closed as desired to discharge fluid or mud from the chamber 13. Beyond the recess 11, the packing box 105 is tapered as at 15 to receive an annular packing seat 16. 17 indicates a gland held to the packing box 9 by bolts 18, the gland 17 engaging packing material 19 surrounding the plunger 5 or 6, and may be screwed 110

down upon such packing by means of the bolts 18 to firmly hold the same against such plunger. The plunger 5 is threaded at its outer end to a cross bar 20 and the plunger 6 is threaded at its outer end to a similar cross bar 21, the cross bars 20 and 21 being rigidly connected together by rods 22 and 22^a, which extend outside of the pump casting. The cross bar 21 is connected to a rod 23 by which the pump may be actuated from any suitable source of power.

Any suitable connection of inlet and exhaust valves may be supplied for the pump chambers 2 and 3, such exhaust and inlet valves being diagrammatically indicated as enclosed within a valve head 24 for the pump, the head 24 carrying inlet valves 25 and 26 connected to inlet line 27 and carrying exhaust valves 28 and 29 connected with discharge line 30.

The plungers 2 and 3 are preferably of substantially less diameter than the entire diameter of the pump chambers 2 and 3, so as to decrease wear upon the pump chambers and inner ends of the plungers. The front ends of the plungers are preferably provided with mud stirring arms 31, which extend below the bottom of the plungers, in order to stir up mud at the bottom of the pump chambers and prevent such mud from becoming packed.

Each of the plungers are preferably provided with a detachable sleeve 32 forming the exterior surface of the plungers so that upon wear of the plungers by replacement of the sleeve, the pump may be repaired without expense or supplying an entire new plunger. The sleeves may be secured to the plungers in any suitable manner as in the drawings the sleeves are indicated as having a closed inner end 33 by which the sleeve may be attached to the plungers by pins 34.

In operation a pump of this class will successfully handle mud or other fluid containing a large amount of foreign matter without placing the operator to a great deal of expense or labor whenever it becomes necessary to repair packing of the pump, the packing being located exteriorly or outside of the pump plunger is readily accessible. Any mud or other foreign matter attempting to work into the packing will be trapped in the mud settling chamber 13 where there is little agitation and such mud or foreign matter will settle and can be removed as desired by opening the cock 14.

Referring to Fig. 5, the mud settling chamber is shown provided with a plurality

of diaphragms 35 extending around the plunger of the pump so as to separate the chamber into a plurality of compartments to assist in maintaining the fluid mud therein in quiescent state, such diaphragms being supported within the chamber in any suitable manner such as by pins 36.

While the form of slush pump herein described is well suited for the purposes of this invention, various modifications may be made in the details of construction without departing from the spirit of the invention. The invention is therefore not limited to the details of slush pump heretofore described, but is of the scope set forth in the appended claims.

We claim:

1. A slush pump comprising a pump chamber, an outside packing plunger operative to reciprocate within the chamber, and mud settling and removing means connected with the chamber.

2. A slush pump comprising a pump chamber, an outside packing plunger operative to reciprocate within the chamber, and mud settling and removing means connected with the chamber between the packing of the plunger and chamber.

3. A slush pump, comprising a pump chamber, an outside packing plunger operative to reciprocate within the chamber, the plunger being of substantially smaller diameter than the diameter of the chamber, and means carried by the plunger operative to prevent mud packing there below.

4. A slush pump, comprising a pump chamber, an outside packing plunger operative to reciprocate within the chamber, mud settling and removing means connected with the chamber and means carried by the plunger to prevent packing of mud there below.

5. A slush pump comprising a pump chamber, an outside packing plunger operative to reciprocate within the chamber, a mud settling chamber connected between the packing of the plunger and said chamber, and a plurality of spaced diaphragms within said mud settling chamber.

Signed at Hardin, Montana, by THOMAS D. CAMPBELL, this 18th day of October, 1924.

Signed at Los Angeles, California, by HALL H. HOLDWAY, this 10th day of September, 1924.
